UNITED STATES PATENT OFFICE.

WILLIAM R. KLOEB, OF HAMILTON, OHIO, ASSIGNOR OF ONE-HALF TO THEODORE NIEMAN,
OF ST. BERNARD, OHIO.

JACKET-RADIATOR.

No. 921,259.

Specification of Letters Patent.

Patented May 11, 1909.

Application filed February 13, 1908. Serial No, 415,661.

To all whom it may concern:

Be it known that I, WILLIAM R. KLOEB, a citizen of the United States, residing at Hamilton, Ohio, have invented a new and useful Improvement in Jacket-Radiators, of which the following is a specification.

My invention relates to jacket radiators of the class adapted to use in connection with jacketed heaters or elsewhere, and the objects of my improvement are to removably inclose a radiator between the fire box and the outer wall of the heater; to heat the radiator with gas, to reinforce the action of the heat from the fire box; to provide the radiator with range water pipes; to provide means for cleaning said pipes; to locate the range pipes directly over the burner to prevent sweating; to provide the radiator with a ventilating chamber having connections with the chimney of the heater for carrying off the gas, should the burner be extinguished without the gas being turned off; and to combine simple and durable construction with facility of operation and efficiency of action. These objects are attained in the following described manner, as illustrated in the accompanying drawings, in which:—

Figure 1 is the front elevation of a heater with parts broken away and parts in section provided with a jacket radiator embodying my improvements; Fig. 2, a horizontal section on the line *a—a* of Fig. 1; Figs. 3 and 4, a plan and front elevation respectively of a radiator with parts broken away, and Fig. 5, a horizontal section on the line *b—b* of Fig. 4. Fig. 6 is a vertical transverse medial section of the radiator taken in the plane indicated by the line *6—6*, Fig. 4.

In the drawings, 1 represents the fire box of a heater, 2 the ash pit, 3 the grate, 4 the drum, 5 the dome, 6 the hot air flues, 7 the smoke flue, and 8 the inclosing wall or jacket, all constructed and arranged in the ordinary manner.

The jacket radiator or supplemental heater consists of a sheet metal box 9 adjustably supported on legs 11 and formed with a lateral curve concentric with the wall 8. The inner wall 12 is removably secured by means of screws 13 and its bottom is formed with one or more openings 14 for the insertion therein of hydrocarbon burners 15. The end walls 16 are preferably tapered on their inner edges toward the top and converged laterally in an inward direction in radial planes with

the axis of the heater. A horizontal partition 17 provided with an opening 18 is removably secured within the radiator by means of screws 19, or by other suitable means, for separating the heating chamber 21 from the ventilating chamber 22 thereover. Obviously one or more of these radiators may be used in connection with the same furnace. Two are shown so used in the drawings at 9 and 9', Figs. 1 and 2. Flues 23 admit air 65 from any convenient source (not shown), while flue 24 from radiator 9 communicates with the smoke flue 7 and flue 24' from radiator 9' opens into the fire-box 1.

Water tubes 27 communicating with a range tank (not shown) are extended horizontally through the heating chamber 21 and directly over the burner 15. A hollow coupling 28 which connects the adjacent ends of the tubes 27 together is provided with 75 plugged openings 29 for permitting the tubes to be inspected or cleaned. An opening 31 in the outer wall of the radiator is provided with a closure 32 as shown in Fig. 6 to admit a taper for igniting the burner 15. Pipes 33 80 provided with cocks 34 admit gas to the burners 15 from a source (not shown). One of these cocks is seen at the right in Fig. 1, the one in the left side pipe 33 being hidden by the projection closed by door 35. The inclosing wall 8 is provided on one side with a door 35 for the insertion of the radiator therethrough and within the annular chamber 36 between said wall and the fire box 1. One or more closed pipes 37 may be extended 90 from the ends 16 of the radiator for increasing the radiating surface thereof if desired.

In operation, one or more radiators may be located within the annular chamber 36 as seen in Fig. 2 and adjusted on legs 11 to the 95 desired height with the ventilating flues and water tubes properly connected. The gas may be admitted to the burners through the pipes 33 and ignited through the openings 31 either for heating the air within the annular chamber 36 or for superheating it when the furnace of the heater is being used. The walls of the fire box prevent the radiation of much of the heat therein to the annular chamber and the radiators serve to supplement the action of the furnace and greatly increase its heating capacity.

In moderate weather, either the furnace of the heater or the radiators may be used separately as desired. The location of the range 110

2
pipes adjacent to and directly over the burner prevents them from sweating and the ventilating chamber 22 together with its connections carries off the gas and prevents the danger of explosion or asphyxiation should the burner become extinguished with the gas turned on.

Having fully described my improvements, what I claim as my invention and desire to secure by Letters Patent of the United States is:—

1. The combination with a jacketed heater provided with a smoke exit passage, of a jacket radiator located between the fire-box and the jacket and comprising a metal box, the lateral walls thereof being concentrically curved and upwardly converged for forming between them a segment of an upwardly tapered annular chamber, a hydrocarbon burner within the box, range pipes thereover, and a ventilating passage leading from the box and adapted to communicate with the smoke exit passage of the jacketed heater.

2. The combination with a jacketed heater, of a jacket radiator located between the fire-box and the jacket and comprising a

laterally curved metal box formed tapering toward the top, a horizontal partition removably placed therein, ventilating tubes communicating with the radiator above said partition, horizontal range pipes extending through the radiator concentric with its curved sides and below said partition and a coupling provided with plug openings for connecting the adjacent ends of the pipes together.

3. A heater comprising a jacket provided with a door, a fire-box therein having a smoke exit, a radiator curved laterally concentric with the jacket, and supporting legs adjustably secured on the radiator, said radiator being removably emplaced through the door and within the jacket and provided with independent means for heating its interior, and also provided with range pipe connections and having ventilating connection with the smoke exit from the fire-box.

WM. R. KLOEB.
